CLAIM

The ornamental design for a fiber optic connector jack, as shown and described.

DESCRIPTION

FIG. 1 is a front perspective view of a fiber optic connector jack showing our new design;

FIG. 2 is a rear perspective view of a fiber optic connector jack showing our new design;

FIG. 3 is a front elevational view thereof;

FIG. 4 is a rear elevational view thereof;

FIG. 5 is a front perspective view of a second embodiment showing our new design;

FIG. 6 is a rear perspective view thereof;

FIG. 7 is a front elevational view thereof; and,

FIG. 8 is a rear elevational view thereof.

The bottom of the connector jack is flat and plain.
